TIMING DEVICE FOR MIXERS

Louis A. Guedel, Indianapolis, Ind., assignor to
Hetherington & Berner Inc., Indianapolis, Ind.,
a corporation of Indiana

Application February 15, 1936, Serial No. 64,130

15 Claims. (Cl. 259—163)

It is the object of my invention to produce a timing device for regulating the operation of a mixing machine whereby to insure that mixing operations will be continued for a predetermined length of time. More specifically, it is my object to produce a timing device for controlling the operation of a mixer used in the production of bituminous paving compositions, the timing device operating to insure that the aggregate will be mixed dry for a predetermined length of time before the addition of the liquid bitumen and that after the addition of the bitumen the two ingredients of the paving composition will be mixed together for a second period of predetermined minimum extent.

A further object of my invention is to produce a timing device which may readily be associated with mixers of different construction, and which can be easily and quickly adjusted to alter the length of each mixing period as may be desired.

In carrying out my invention I associate with the mixer suitable charging means, such as weigh-buckets for the aggregate and bitumen respectively, each of such buckets being provided with a valve or gate controlling its discharge into the mixer. The timing device, which is conveniently driven from the mixer, is so associated with the charging means and the discharging means of the mixer as to insure that no bitumen can be added to the mixer until the expiration of a predetermined dry-mixing period following the admission of the aggregate and also to insure that the batch can not be discharged from the mixer until the expiration of a predetermined wet-mixing period following the opening of the bitumen valve. I may so construct the device as to provide for two wet-mixing periods of predetermined extent separated by an interval in which additional aggregate is supplied to the mix.

The accompanying drawings illustrate my invention: Fig. 1 is an end elevation of the mixing plant, showing the mixer, the bitumen and aggregate weigh-buckets, and the timing device; Fig. 2 is a front elevation of a timing device with its cover removed; Fig. 3 is a fragmental end elevation of the timing device with a slight modification; Fig. 4 is a horizontal section on the line 4—4 of Fig. 2; Fig. 5 is a fragmental view generally similar to Fig. 2 but showing the moving parts in different positions; Fig. 6 is a view similar to Fig. 2 but showing a slightly modified form of timing device adapted to provide three mixing periods of measured extent; Fig. 7 is an elevation of the cam arrangement; and Fig. 8 is a fragmental plan on the line 8—8 of Fig. 6.

The mixer 10 shown in the drawings is of the pugmill type and has one or more rotatable shafts 11 carrying blades 12 by means of which material in the mixer is agitated. While I have shown a mixer of this particular type, it is to be understood that my invention may be used with mixers of other kinds.

Associated with the mixer 10 is suitable charging means, here shown as an aggregate weigh-bucket 15, having a discharge valve 16, and a bitumen weigh-bucket 17, having a discharge valve 18. The mixer is shown as having in its bottom a sliding discharge gate 19 which may conveniently be operated by fluid pressure. To this end, the gate is provided with a cylinder 20 receiving a stationary piston 21 mounted on a rod 22 on which the cylinder is slidable. The rod is provided with two longitudinally extending passages which open into the cylinder on opposite sides of the piston 21 and which communicate respectively with pipes 23 and 24 leading to a suitable valve 25 by the operation of which either of the pipes 23 and 24 may be connected to a fluid supply line 26 while the other is connected to an exhaust line 27.

As shown, the three valve 16, 18, and 25 are manually operated, the valve 16 having an operating handle 30, the valve 18 having an operating handle 31, and the valve 25 having an operating handle 32. Each of the valves has associated with it a lock of any convenient form controlling its operation. In the construction shown in Figs. 1, 2, and 3, the locks are shown as directly associated with the valve-operating members, but this is not at all essential.

As shown in Figs. 1 and 3, the operating handle 30 of the aggregate valve 16 is provided with an abutment 35 disposed adjacent a swinging segment 36, which, when disposed below the abutment 35, will prevent that downward movement of the handle 30 which is necessary to open the valve 16 but which, in its normal position, is disposed at one side of the path of downward movement of the abutment 35 so as not to interfere with opening of the valve 16. The segment 36 is shown in Fig. 1 as swingable in a plane parallel to the path of movement of the handle 30 and in Fig. 3 as swingable in a plane perpendicular to the path of movement of the handle 30; but the particular arrangement of the segment 36 is immaterial so long as it may swing into and out of position beneath the abutment 35. The bitumen valve is shown as locked through the medium of a disk 38 which is rigid with that valve and its operating handle 31.

and which is provided with a radial slot for the reception of a retractable tongue 39 which, when engaged in the slot, prevents opening of the bitumen valve. The valve 25, controlling discharge from the mixer, is controlled by a disk 40 which is associated with the rotatable element of the valve and which is notched as at 41 for the reception of a locking member 42. When the locking member 42 is engaged in the notch 41, the valve 25 is held in that position of adjustment which effects or maintains closing of the gate 19. The specific form of valve-operating devices and locks therefor illustrated in the drawings forms no part of my invention in its broader aspects, as these features are susceptible of considerable variation to meet the characteristics of the mixer and of its charging and discharging means with which my timing device is to be associated.

In the arrangement illustrated in Figs. 1 to 5, a movable control member for all the valves is provided in the form of a vertically slideable bar 50 mounted in and projecting above the top of a casing 51 in which the timing mechanism is enclosed. Conveniently, there is secured to the bar 50 near the top thereof a rod 52 which extends downwardly outside the casing 51. The tongue 39, which controls the bitumen-valve in the manner above set forth, is mounted on the rod 52 to be vertically movable therewith; while near the top of the rod 52 there is provided an ear 53 having a pin-and-slot connection with the segment 36 to swing this segment as the rod 52 moves vertically with the bar 50. The bar 50 is shown as being provided within the casing 51 with a cam-slot 54 associated with which is a cam-follower 54' connected to the locking member 42 which controls the valve 25.

The rod 50 has three controlling positions—namely, a lower position, an intermediate position, and an upper position. In the lower position, shown in full lines in Figs. 2 and 3, the tongue 39 is engaged in the slot of the disk 38 to lock the bitumen valve in closed position; but the segment 36 is out of the path of movement of the abutment 35 on the handle 30 for the aggregate valve, and the locking member 42 associated with the valve 25 is retracted. In the intermediate position of the bar 50, shown in dotted lines in Figs. 2 and 3, the tongue 39 is still engaged in the slot of the disk 38 to lock the bitumen valve closed; the segment 36 has been swung beneath the abutment 35 to prevent the downward movement of the handle 30 which effects opening of the aggregate valve 16; and the locking member 42 is extended outwardly into the notch 41 to lock the valve 25 in the position shown in Fig. 1. In the extreme upper position of the rod 50, the tongue 39 is disengaged from the slot in the disk 38 to permit opening of the bitumen-valve 18; but the segment 36 and locking member 42 are still effective to prevent opening of the aggregate valve 16 and any movement of the valve 25.

The control rod 50 is manually movable. Its upper and lower limits of movement are defined in any convenient manner. For example, the lower limit of movement of the rod 50 may be defined by engagement of the rod with the bottom of the casing 51, while its upward movement may be limited by engagement of a stationary guide 56 with the lower end of a longitudinally extending guide slot 57 in the rod. The intermediate position of the rod is defined by a retractable stop 58 normally positioned to engage an abutment 59 secured to the rod 50 near the

lower end thereof. A swinging latch 60 co-operating with an ear 61 on the rod 50 serves to maintain the rod in its intermediate position.

The timing mechanism embodied in my device operates to control the respective positions of the stop 58 and latch 60. To this end, the latch 60 may be in the form of a swinging arm pivotally mounted upon a stud or screw 62 supported from the casing 51, and the stop 58 may be in the form of a projection on a swinging arm 63 also mounted on the pivot member 62. Yielding means, such as leaf springs 64, normally operate to hold the latch 60 in the position shown in Fig. 5 and the arm 63 in the position shown in Fig. 2, in which positions the latch 60 is operative to engage the ear 61 and the stop 58 is positioned to engage the abutment 59.

Movement of the stop 58 and latch member 60 to their respective retracted positions is effected by two cam members 65 and 66 which are secured to a rotatable element 67 to rotate therewith, but which are angularly adjustable relatively to each other and to the rotatable element. Conveniently, the element 67 is in the form of a sleeve rotatably mounted upon a stationary stub shaft 68, as is clear from Fig. 4. Rigid with the sleeve 67 as by being integral therewith, is an annular flange or collar 69 to which the cams 65 and 66 are adjustably secured. As shown, the flange 69 is provided with an annular series of holes for the reception of bolts 70 which also pass through holes in the cam member 65 which may be disposed against the rear face of the flange 69. In addition, the bolts 70 pass through a spacing collar 71, a bearing collar 72, and a disk 73, which are located successively in rear of the cam member 65. The cam member 66 is rotatable on the bearing collar 72, its position relative to the sleeve 67 being maintained by a screw 74 which passes through a slot 75 in the cam member into any one of a series of holes 76 in the disk 73.

Secured to the sleeve 67 on the front face of the flange 69 is an arm 78 having in its outer end a stop 79 which co-operates with an adjustable abutment 80, conveniently in the form of a screw mounted in a bracket 81 on the side wall of the casing 51, to determine the zero position of the sleeve 67 and the cam members 65 and 66 which rotate with it. As shown in the drawings, the sleeve 67 is rotated from zero position by means of a gear 83 which is secured to the sleeve. A torsion spring 84 acting between the stationary stub shaft 68 and the gear 83 tends to rotate the sleeve 67 in a clockwise direction to cause engagement of the stop 79 with the abutment 80.

Conveniently, the gear 83 is in the form of a worm gear and is driven from the shaft 11 of the mixer to which it is releasably connected through any train of driving mechanism. As shown, one of the shafts 11 is provided with a worm gear 85 driving a sprocket 86 connected by a chain 87 to a second sprocket 88 which is rigidly mounted upon the end of a shaft 89 supported in suitable bearings 90 within the casing 51. Within the casing 51, the shaft 89 bears a worm 91 meshing with a worm gear 92 carried by a shaft 93 which is rotatably mounted in a suitable sub-frame 94. The sub-frame 94 is rocked about the axis of the shaft 89 and worm 91 to carry into and out of engagement with the worm wheel 83 a worm 95 which is mounted on the shaft 93 for rotation therewith.

When the sub-frame 94 is in the full-line position shown in Fig. 2, the worm 95 is disengaged from the worm wheel 83, and that worm wheel is

therefore stationary. When, however, the sub-frame 94 is rocked to carry the worm 95 into engagement with the worm wheel 83, the worm wheel and the parts rotatable with it will be rotated about the axis of the stub shaft 68 under power transmitted from the shaft 11 through the gearing 85 and 87.

Conveniently, the sub-frame 94 and the parts it carries are so arranged that their center of gravity is spaced horizontally a considerable distance from the axis of the shaft 89, so that under the influence of the force of gravity the sub-frame will normally occupy the full-line position shown in Fig. 2, with the worm 95 disengaged from the worm wheel 83. Movement of the sub-frame 94 to effect engagement of the worm 95 and worm wheel 83 may conveniently be effected through the medium of a sub-frame extension 96 which projects upwardly into association with the rear end of a push-rod 97 adapted to be moved longitudinally of itself by a cam member 98 mounted on the bar 50.

In operation, the movable parts of the device just described normally occupy the position illustrated in Fig. 1 and in full-lines in Figs. 2 and 3. When the operator desires to mix a batch of bitumen and aggregate, he first supplies the aggregate to the mixer, as by depressing the handle 30 to open the valve 16 and empty the contents of the aggregate weigh-buckets into the mixer 10. The operator then raises the bar 50 to its intermediate position, which is determined by engagement of the stop 58 with the abutment 59. In this position of the bar 50, the latch 60 engages the tooth 61 to prevent the bar from returning to its lower position. Conveniently, there is associated with the bar 50 a bar-raising lever 100 which is fulcrumed on a bracket 101 supported from the casing 51 and which is operatively connected to the bar 50 in any convenient fashion. A chain 102, or other flexible tension-transmitting element, may lead to the operator's station to facilitate convenient raising of the bar 50.

Upon the raising of the bar 50 to its intermediate position, the locking member 42 is forced outwardly by the walls of the cam-slot 54 to engage the notch 41 in the locking-disk 40 of the valve 25, and the sub-frame 94 is rocked to bring the worm 95 into engagement with the worm wheel 83, all as indicated in dotted-lines in Fig. 2. The rod 52 and tongue 39 move upwardly with the bar 50, but this movement, as is clear from the dotted-line showing in Fig. 3, is insufficient to free the tongue 39 from engagement with the slot in the disk 38 associated with the bitumen valve.

As the mixer operates, it drives the timing mechanism to rotate the gear 83 and the cam members 65 and 66 in a counterclockwise direction. After the expiration of a predetermined interval, the duration of which is determined by the original setting of the cam member 65, the head of the cam member strikes the upper end 65 of the arm 63 and moves the stop 58 from its normal position above the abutment 59, as shown in Fig. 5, thus permitting further upward movement of the bar 50. The occurrence of this event is signaled to the operator as by means of a lamp 105 which is supplied with current under the control of a switch 106 conveniently arranged to be closed by swinging of the arm 63 when the stop 58 is retracted. The head of the cam 65 is so shaped as to maintain the stop 58 retracted and the lamp 105 illuminated for a convenient

interval—say approximately 15 seconds. During this interval, the operator, by applying tension to the chain 102, raises the bar 50 to the limit of its upward movement, thus freeing the tongue 39 from engagement with its slot in the disk 38 and thereby permitting the operator to add bitumen to the mix by depressing the handle 31 to discharge the contents of the bitumen weigh-bucket 17 into the mixer. Upon return of the bitumen valve to closed position, the slot in the disk 38 again comes into alignment with the tongue 39, thus permitting the bar 50 to drop until the tooth 61 strikes the latch 60. As the mixer continues to operate, the cams 65 and 66 continue to rotate in the counterclockwise direction until the head of the cam member 66 strikes the upper end of the latch 60, releasing it from its engaged position and permitting the bar 50 to be returned to its lower or normal position shown in full-lines in Fig. 2. The return of the bar 50 to normal position retracts the locking member 42 and permits the operator to manipulate the valve 25 to open the dump-gate 19 in the bottom of the mixer.

As the gear 83 rotates during the mixing periods, the spring 84 is tensioned; and when the return of the bar 50 to its normal position causes disengagement of the worm 95 from the worm wheel 83 the spring 84 operates to return the worm wheel and the cams to their normal position, which is determined by engagement of the stop 79 with the abutment 80.

The duration of the dry-mix period is controlled by the position of the adjustable abutment 80, while the duration of the wet-mix period is controlled by the position of the cam 66 relative to the cam 65.

It is to be noted that the emptying of the aggregate bucket into the mixer must precede the starting of the timing device; as the movement of the bar 50 which initiates operation of the timing device swings the segment 36 beneath the abutment 35 on the handle 30 and therefore prevents opening of the aggregate valve 16 until after the timing cycle has been completed. As the bitumen valve can not be opened until retraction of the stop 58, a minimum dry-mix period is thereby effected.

It is to be noted further that the bitumen valve 18 can be opened only when the bar 50 is raised to its uppermost position and that the bar 50 can only be elevated to its upper position while the stop 58 is being held in retracted position by the cam member 65.

The modification of my invention illustrated in Figs. 6, 7, and 8 is in general intended for the same use as the modification already described; but it provides an additional mixing period of controlled duration and also embodies a somewhat different means for controlling the supply of aggregate to the mixer. This modification is particularly suited to control a process in which a second quantity of aggregate, usually a fine aggregate such as limestone dust, is added to the primary mixture of aggregate and binder after the expiration of successive dry-mix and wet-mix periods.

The device of Figs. 6, 7, and 8 embodies the same vertically slidable member 50 as the other modification, and movements of the member 50 are controlled by the same latch 60 and swinging arm 63 as are employed in the other modification. Instead of controlling opening of the aggregate valve through the medium of the mem-

ber 50, however, I control it by means of a special cam rotatable with the gear 83.

As indicated in Fig. 6, some member 30' connected to the aggregate valve for movement therewith, which member may be a valve-operating lever like the lever 30 but movable upwardly to open the aggregate valve and downwardly to close it, is disposed at one side of the casing 51 in association with a latch 115. When the aggregate valve is closed, the member 30' occupies the full-line position shown in Fig. 6, and when the aggregate valve is open the member 30' occupies the dotted-line position. The latch member 115, which is shown as pivotally mounted on the side of the casing 51, acts when in operative position to retain the member 30' in its lower position and thus to prevent opening of the aggregate valve.

The latch 115 is controlled by a suitable latch-operating cam rotatable with the worm gear 83. As is clear from Fig. 7, this cam is a composite structure including a spider 116 which supports a ring 117 upon which three adjustable cam-segments 118, 119, and 120 are mounted. Conveniently, the ring 117 is provided with a plurality of arcuate slots through which pass screws 121 holding the various cam-segments 118, 119, and 120 in place.

Co-operating with the cam-segments 118, 119, and 120 is a cam-roller 123 mounted on a swinging arm 124 the free end of which is connected by a link 125 to the latch 115 in such a way that whenever any of the cam-segments engages the roller 123 the latch 115 will occupy its operative position in which it prevents opening of the aggregate-valve. The latch 115 is biased to released position by any convenient means such, for example, as a spring 115' which, to simplify illustration, is shown in the drawings as being located outside the casing 51 but which can be arranged in any convenient position or manner to perform its intended function. As shown in the drawings, the cam segments 118, 119, and 120 are so arranged as to move the latch to operative position as soon as the worm gear 83 begins to rotate, to hold the latch 115 in operative position for an interval, to release it for a second interval, and to return it to operative position thereafter.

Mounted on the swinging arm 124, I have shown a switch contact 135 which engages a stationary contact 136 when the latch 115 is in inoperative position, but which is moved out of engagement with the fixed contact 136 when the latch 115 is moved to operative position. In series with the contact 136 is a suitable signal, here shown as a lamp 137. The device shown in Figs. 6, 7, and 8 also includes the signal lamp 105 previously described, but shows a somewhat different arrangement for the switch controlling that lamp. In this arrangement, the lamp 105 is connected in series with a stationary spring-contact 140 and a movable spring contact 141, the latter being mounted upon one arm of a bell crank 142 swingable about a vertical axis. The other end of the bell crank 142 is pivotally connected to the swinging arm 63 which carries the stop 58, the arrangement being such that when the stop 58 is in advanced position the switch 140—141 will be open.

In most respects, the device illustrated in Figs. 6, 7, and 8 operates similarly to that previously described. Normally, the parts occupy the positions respectively shown in Fig. 6. At the start of a mixing operation, a charge of aggregate of proper weight is placed in the aggregate weigh-bucket 15 of Fig. 1. This charge of aggregate is

permitted to pass to the mixer by opening the aggregate valve 16, which opening movement involves movement of the member 30' from the full-line to the dotted-line position of Fig. 6. When the initial charge of aggregate has been supplied to the mixer, the aggregate valve 16 is closed and the member 30' returned to its full-line position. The member 50 is then raised to its intermediate position, as in the case of the device shown in Figs. 1 to 5 inclusive. This movement of the member 50 locks the mixer-discharge device in closed position and throws the worm 95 into mesh with the worm-gear 83 to cause rotation of the worm gear 83 and the cams rotatable with it. As is the case in the device shown in Figs. 1 to 5, movement of the control member 50 to its intermediate position does not unlock the bitumen valve.

Immediately after the worm gear 83 begins to rotate, the cam-segment 120 engages the roller 123 and moves the latch 115 to its operative position to prevent opening of the aggregate-valve. As rotation of the worm gear 83 continues and while the latch 115 is still held in operative position by either or both of the cam-segments 119 and 120, the cam member 65 engages the swinging arm 63 and retracts the stop 58 to determine the termination of the dry-mix period. This movement of the arm 63 also closes the switch 140—141 and lights the lamp 105. The operator, being advised of the retraction of the stop 58 by the lighting of the lamp 105, raises the member 50 to its extreme position, thus unlocking the bitumen valve and permitting the bitumen in the weigh-bucket 17 to be added to the aggregate previously supplied to the mixer. After all bitumen in the weigh-bucket 17 is drained into the mixer, the bitumen-valve 18 is closed and the member 50 permitted to drop to its intermediate position.

As rotation of the cams continue and before the cam 66 engages the latch 60, the cam-segments 119 and 120 are carried out of engagement with the roller 123 to permit the latch 115 to return to its inoperative position shown in Fig. 6, under the influence of the spring 115'. During the dry-mix period following the admission to the mixer of the original aggregate-supply, the aggregate weigh-bucket has been filled with the second quantity of aggregate. When the latch member 115 is retracted as just described, the switch 135—136 is closed to cause lighting of the signal lamp 137. During the interval in which the lamp 137 is lighted and the latch 115 retracted, the operator opens the aggregate-valve to discharge the second charge of aggregate into the mixer, following which the aggregate valve is again closed and the member 30' is restored to its full-line position.

At the conclusion of the interval provided for the addition of the second charge of aggregate, the cam-segment 118 engages the roller 123, opens the switch 135—136, and moves the latch 115 to operative position. The cam segment 118 has sufficient extent to hold the latch member 115 in operative position until after the cam 66 has engaged and retracted the latch 60 to permit the member 50 to drop and release the discharge valve 25, which is then operated to discharge the contents of the mixer.

The cam segment 119 is adjustable circumferentially of the ring 117 independently of the segment 120 to control the duration of the first dry-mix period, while the same segment 118 is also adjustable to provide any desired interval for the addition of the bitumen irrespective of the 75

- position of the cam-segment 119. If it is desired to use the device of Figs. 6, 7, and 8 to accomplish the same result as the device of Figs. 1 to 5, the cam-segment 119 can be moved to close the gap between the segments 118 and 120 and thus to hold the latch member 115 continuously in operative position and to prevent any opening of the aggregate valve at any time after a timing cycle has once been started.
- 10 I claim as my invention:
1. In combination with a mixer, a binder-supply device and an aggregate-supply device therefor, a discharge device for said mixer, locks actuatable respectively to render said supply and discharge devices inoperative, a movable member movable from a normal position through an intermediate position to an extreme position, means controlled by said movable member and acting when said member is in any but its normal position to actuate the locks for said aggregate-supply and discharge devices, means controlled by said movable member and acting when said member is in any but its extreme position to actuate the lock for said binder-supply device, timing means, and mechanism controlled by said timing means for preventing movement of said member from its intermediate position until after the expiration of a predetermined time following its movement into such intermediate position.
  2. In combination with a mixer, a binder-supply device and an aggregate-supply device therefor, a discharge device for said mixer, locks actuatable respectively to render said supply and discharge devices inoperative, a movable member movable from a normal position through an intermediate position to an extreme position, means controlled by said movable member and acting when said member is in any but its normal position to actuate the locks for said aggregate-supply and discharge devices, means controlled by said movable member and acting when said member is in any but its extreme position to actuate the lock for said binder-supply device, a retractable stop for preventing movement of said member from its intermediate position to its extreme position, a releasable latch for preventing movement of said member from its intermediate position to its normal position, and timing means set in operation by movement of said member from its normal position to its intermediate position for temporarily retracting said stop and subsequently releasing said latch, said member being biased toward its normal position.
  3. In combination with a mixer, a charging device and a discharging device therefor, locks respectively associated with said devices, timing means operable at a predetermined time after actuation to release the lock for the discharging device, and a control member manually movable independently of said charging device to simultaneously operate the lock for the charging device and actuate said timing means, said charging device being operable to effect a charging operation without moving said control member.
  4. In combination with a mixer, a charging device therefor, a timing device, a control member for actuating said timing device independently of said charging device, a lock for said charging device operable upon actuation of said timing means, and connections controlled by said timing device for releasing said lock upon the expiration of a predetermined time following actuation of said timing means, said charging device being operable to effect a charging operation without moving said control member.
  5. In combination with a mixer, a charging device therefor, a lock for said charging device, timing means operable upon a single actuation to lock said lock, to maintain it locked for a pre-

determined interval, to release it for a second and independently predetermined interval, and to again lock it, a signal device, and means operable during said second interval for operating said signal device.

6. In combination with a mixer, a binder-supply device and an aggregate-supply device therefor, a discharge device for said mixer, locks actuatable respectively to render said supply and discharge devices inoperative, a movable member movable from a normal position through an intermediate position to an extreme position, means controlled by said movable member and acting when said member is in any but its normal position to actuate the locks for said aggregate-supply and discharge devices, means controlled by said movable member and acting when said member is in any but its extreme position to actuate the lock for said binder-supply device, a retractable stop for preventing movement of said member from its intermediate position to its extreme position, a releasable latch for preventing movement of said member from its intermediate position to its normal position, and timing means set in operation by movement of said member from its normal position to its intermediate position for temporarily retracting said stop and subsequently releasing said latch, said member being biased toward its normal position.

7. In combination with a mixer, a binder-supply device and an aggregate-supply device therefor, a discharge device for said mixer, locks actuatable respectively to render said supply and discharge devices inoperative, a movable member movable from a normal position through an intermediate position to an extreme position, means controlled by said movable member and acting when said member is in any but its normal position to actuate the locks for said aggregate-supply and discharge devices, means controlled by said movable member and acting when said member is in any but its extreme position to actuate the lock for said binder-supply device, a retractable stop for preventing movement of said member from its intermediate position to its extreme position, a releasable latch for preventing movement of said member from its intermediate position to its normal position, and timing means set in operation by movement of said member from its normal position to its intermediate position for temporarily retracting said stop and subsequently releasing said latch.

8. In combination with a mixer, a binder-supply device and an aggregate-supply device therefor, a discharge device for said mixer, locks actuatable respectively to render said supply and discharge devices inoperative, a movable member movable from a normal position through an intermediate position to an extreme position, means controlled by said movable member and acting when said member is in any but its normal position to actuate the locks for said aggregate-supply and discharge devices, means controlled by said movable member and acting when said member is in any but its extreme position to actuate the lock for said binder-supply device, a retractable stop for preventing movement of said member from its intermediate position to its extreme position, and timing means set in operation by movement of said member from its normal position to its intermediate position for temporarily retracting said stop, said member being biased toward its normal position.

9. In combination with a mixer, a binder-supply device and an aggregate-supply device there-

for, a discharge device for said mixer, locks actuating respectively to render said supply and discharge devices inoperative, a movable member movable from a normal position through an intermediate position to an extreme position, means controlled by said movable member and acting when said member is in any but its normal position to actuate the locks for said aggregate-supply and discharge devices, means controlled by said movable member and acting when said member is in any but its extreme position to actuate the lock for said binder-supply device, a retractable stop for preventing movement of said member from its intermediate position to its extreme position, and timing means set in operation by movement of said member from its normal position to its intermediate position for temporarily retracting said stop.

10. In combination with a mixer, a binder-supply device and an aggregate-supply device therefor, a discharge device for said mixer, locks actuating respectively to render said supply and discharge devices inoperative, a movable member movable from a normal position through an intermediate position to an extreme position, means controlled by said movable member and acting when said member is in any but its normal position to actuate the locks for said aggregate-supply and discharge devices, means controlled by said movable member and acting when said member is in any but its extreme position to actuate the lock for said binder-supply device, a retractable stop for preventing movement of said member from its intermediate position to its extreme position, and timing means for temporarily retracting said stop, said member being biased toward its normal position.

20. 11. In combination with a mixer, a binder-supply device and an aggregate-supply device therefor, a discharge device for said mixer, locks actuating respectively to render said supply and discharge devices inoperative, a movable member movable from a normal position through an intermediate position to an extreme position, means controlled by said movable member and acting when said member is in any but its normal position to actuate the locks for said aggregate-supply and discharge devices, means controlled by said movable member and acting when said member is in any but its extreme position to actuate the lock for said binder-supply device, a retractable stop for preventing movement of said member from its intermediate position to its normal position, and timing means for temporarily retracting said stop and subsequently releasing said latch, said member being biased toward its normal position.

30. 12. In combination with a mixer, a binder-supply device and an aggregate-supply device therefor, a discharge device for said mixer, locks actuating respectively to render said supply and discharge devices inoperative, a movable member movable from a normal position through an intermediate position to an extreme position, means controlled by said movable member and acting when said member is in any but its normal position to actuate the locks for said aggregate-supply and discharge devices, means controlled by said movable member and acting when said member is in any but its extreme position to actuate the lock for said binder-supply device, a retractable stop for preventing movement of said member from its intermediate position to its extreme position, and timing means for temporarily retracting said stop, said member being biased toward its normal position.

40. 13. In combination with a mixer, a binder-supply device and an aggregate-supply device therefor, a discharge device for said mixer, locks actuating respectively to render said supply and discharge devices inoperative, a movable member movable from a normal position through an intermediate position to an extreme position, means controlled by said movable member and acting when said member is in any but its normal position to actuate the locks for said aggregate-supply and discharge devices, means controlled by said movable member and acting when said member is in any but its extreme position to actuate the lock for said binder-supply device, a retractable stop for preventing movement of said member from its intermediate position to its extreme position, and timing means for temporarily retracting said stop.

50. 14. In combination with a mixer, a charging device therefor, a lock operative to prevent operation of said charging device, and a timing means for controlling operation of said lock, said timing means including a rotatable member, a pair of circumferentially overlapping cam-segments mounted for relative circumferential adjustment on said rotatable member, a third cam segment mounted on said rotatable member and adjustable circumferentially toward and away from said pair of overlapping cam segments, and a cam follower operatively connected to said lock to render the lock operative when engaged by any of said cam-segments.

60. 15. The invention as set forth in claim 5 with the addition of a discharge device for said mixer, a lock for said discharge device, and mechanism operable by said timing means for maintaining said discharge-device locked during such predetermined intervals.

LOUIS A. GUEDEL. 60
